US LLP(57) **CLAIM**

The ornamental design for tire balancing weight, as shown and described.

DESCRIPTION

FIG. 1 is a perspective view of the first embodiment of my design for balancing weight for tires that are attached to an adhesive foam tape.

FIG. 2 is a top view of the first embodiment;

FIG. 3 is a bottom view of the first embodiment;

FIG. 4 is a left side view of the first embodiment, the right side view being a mirror image thereof; and,

FIG. 5 is a front view of the first embodiment, the rear view being a mirror image thereof.

All other surface(s) or portion(s) of the tire balancing weight not shown in the figures or otherwise described in the specification form no part of the claimed design.
